RUSTIC GATEWAY

Olin O. Emery, Longmont, Colo.

Application May 25, 1959, Serial No. 56,060

Term of patent 7 years

(Cl. D28—1)

Figure 1 is a front view, partly in perspective, of a rustic gateway showing my new design, the sides of the bison and eagles not shown being substantially like the sides shown, and the rear of the posts and lintel being substantially plain;

Figure 2 is a transverse cross-sectional view thereof taken along line 2—2 in Figure 1;

Figure 3 is a transverse sectional view taken along line 3—3 in Figure 1, and

Figure 4 is a transverse sectional view taken along line 4—4 in Figure 1.

The dominant features of the design are shown in full lines.

I claim:

The ornamental design for a rustic gateway, as shown and described.
